(57) CLAIM

The ornamental design for a game piece, as shown and described.

DESCRIPTION

FIG. 1 is a perspective view of a game piece showing our new design;

FIG. 2 is a front elevational view thereof, the rear elevational view is unclaimed;

FIG. 3 is a right-side elevational view thereof;

FIG. 4 the left-side elevational view thereof;

FIG. 5 is a top plan view thereof; and,

FIG. 6 is a bottom plan view thereof.

Broken lines in the figures show portions of the game piece that form no part of the claimed design.
